UNITED STATES PATENT OFFICE.

WILLIAM HUNTLEY HAMPTON, OF NEW YORK, N. Y.

PROCESS OF AND APPARATUS FOR TREATING SHALE AND THE LIKE.

Application filed December 11, 1919. Serial No. 344,016.

This invention relates to processes of and apparatus for treating shale and the like; and it comprises more particularly a process of and apparatus for digesting bituminiferous solids, such as shale or the like, with a hydrocarbon oil to extract valuable bituminous matter therefrom, and refining the digestion products in a systematic and economical manner, as hereinafter set forth.

10 In accordance with the process of the invention, the shale or other bituminiferous solid to be treated is thoroughly digested in finely divided condition with an oil admixed therewith, the digestion being conducted at temperatures sufficiently high to effect substantially complete liquefaction and solution of the bitumens present in the shale. During the digestion, certain oil fractions distill off; and these vaporized fractions are conducted directly to refining apparatus for further treatment. The heavier fractions which are not volatilized during the digestion and which remain mixed with residual solid mineral matter are then subjected to suitable treatment for separation of such residual mineral matter, most desirably by diluting the mixture with a lighter oil fraction, and then filtering and washing in centrifugal apparatus. The mixture of oils thus obtained 20 may then be further treated for separation into desirable commercial fractions.

25 While the process of the invention in its broader aspects is concerned with the recovery of valuable hydrocarbons from bituminiferous solid matter generally, it is especially applicable to the treatment of oil-bearing shales, sands, etc. For the sake of a concrete example to illustrate more fully the underlying principles of the invention, the treatment 30 of shale in accordance with the present process will be more particularly hereinafter described; and novel apparatus especially suitable for carrying out such treatment of bituminous shale will also be described, although 35 it is to be understood that the process may be carried out in apparatus differing in many particulars from that here shown for purpose of illustration.

40 Referring to the accompanying drawings which show more or less diagrammatically one system of apparatus in which the novel process may be practiced.

45 Figs. 1 and 2, which are to be considered together, but which are for convenience placed on separate sheets, illustrate a complete sys-

tem in side elevation parts being shown in section.

50 In carrying out the present process of treating shale with the aid of the apparatus here illustrated, more or less finely crushed oil-bearing shale, is fed from a supply bin 10 by conveyor 11, to a combined mixer and heater 12, to which a suitable extraction or digestion oil is simultaneously fed from either of two storage tanks 13, 14, through supply pipe 15 which includes a preheating coil 16, suitably disposed within an enlargement 17 of the flue 18, through which flue pass hot gases from the furnace 19 of the heater 12. The preheated digestion oil thus fed to the mixer may vary widely in character, but ordinarily it is most convenient and desirable to employ a relatively heavy oil, such as a "stripped" oil, that is, an oil from which the lighter fractions have already been removed by some distillation method. Heavy residual oils from practically any source are suitable, however; and in one especially desirable embodiment of the invention, to be more fully referred to hereinafter, crude petroleum serves as the digestion oil to be mixed with the crushed shale in combined heater and mixer 12. The proportion of oil used may vary considerably; but in a typical example, about equal volumes of shale and oil 60 give a satisfactory mixture. Where the digestion oil initially mixed with the crushed shale contains light fractions, as in the case of crude petroleum hereinafter referred to, a larger quantity of oil is added at the outset 65 in order that the residual mixture obtained after the digestion treatment is completed shall have the proper degree of fluidity.

70 In the present specific example, the crushed shale and oil are thoroughly mixed by means of suitable agitator means such as helical conveyors 20, so arranged within the mixer 12 as to advance the mixture toward the discharge end of the mixer, whence the mixture passes through discharge conduit 21, into a 75 grinding device 22, which may be of any appropriate type but which is most desirably a ball or tube mill, provided with a heat insulating housing 23. In this grinder the mixture of shale and oil, which should be at 80 a temperature of around 300 degrees F. or somewhat higher for best results, is treated in the grinder until the shale has been pulverized to the necessary extent. The finer the grinding, the better. In practice, it has 85

90 95 100 105 110

been found that best results are obtained when the grinding is carried so far that 60 per cent or more of the solid matter will pass a 200-mesh sieve. The mixture of finely ground shale and oil, which at this stage may be a semi-fluid pasty mass (using about equal quantities of digestion oil and crushed shale, by volume, in the mixture) is then conducted through conduit 24 into a digesting or heating system which in this particular instance comprises three digesters or retorts 25, 26 and 27 arranged in series, wherein the mixture is gradually brought to a temperature of between 500 and 700 degrees F., temperatures of about 665 to 675 degrees F. in the final retort 27, of the series, being good practice. Each of these digesters is provided with means such as a screw conveyer 28, for gradually advancing the fluid mass through the digester system and preventing accumulation of solid materials on the bottom of the retorts. Material passes from digester 25 to digester 26 through a suitable conduit 29, and a similar conduit 30 affords connection between digesters 26 and 27, while suitable furnace means 29 provide the necessary heat for the digesters. The vapor off-takes 31 of the digesters may all lead into a common vapor main 32. Steam or an inert gas may be introduced into the mixture undergoing digestion, or caused to sweep over the surface thereof, to facilitate vaporization of certain fractions at a lower temperature than would be otherwise required to volatilize them. Through these off-takes pass the vapors of those fractions of the oils in the digesters that are volatilizable under the conditions of operation; and these vapors while still hot are most desirably conducted directly to treating and refining apparatus for the production of commercial fractions. In the present example such further treatment comprises superheating of the vapors in the presence of admixed steam, followed by fractional condensation. As here shown, a steam injector 33 draws the oil vapors from 32 and forces the mixture of steam and oil vapors through coiled pipe superheaters 34 and 35, the mixture attaining considerably higher temperatures in these superheaters than the maximum digester temperatures. Where desirable, the injector may be operated to create subatmospheric pressure in the digesters and thus to facilitate vaporization therein; and, as stated, steam may also be introduced into the digestion mixture or blown over the surface to aid in driving off certain fractions. In practice the temperatures in the superheaters may attain 900° or 1000° F. or more, 1300° F. being attained in some cases. By this treatment the heavier portions of the volatilized oil fractions are to a great extent cracked or broken down to give lighter fractions. Any tarry products deposited in the coils of the superheater may be trapped off through valved connections 36 into a common down pipe 37, which leads to a collection tank 38, from which the collected heavy products may be removed through valved outlet 39 and conducted to supply tanks 13, 14, 70 in any convenient manner, or otherwise disposed of. The highly heated vapors leaving the superheater at 40, pass through a cooling and condensing system, shown here as comprising two chambers 41 and 42, but which may comprise as many chambers as may be desirable, wherein certain relatively heavy fractions which may still be present in the vapors, together with more or less water, are condensed out and dropped to the bottom of the chambers. By suitably designing the chambers 41 and 42, and properly regulating the operating conditions, lubricating and the heavier kerosene fractions may be fractionated out in these chambers. The vapors leaving chamber 42, and containing some kerosene fractions and still lighter fractions, are then most desirably subjected to a washing treatment. In the present example the vapors from chamber 42 pass down through pipe 43 which dips below the surface of water contained in a wash tank 44. This treatment removes resinous and other matters which would tend to discolor succeeding condensed fractions, and a part of the kerosene may also collect there and be drawn off through outlet 44a. The washed vapors leave the wash tank through pipe 45 and are led through another series of cooling and condensing chambers 46, 47, of which there may be any desired number, similar in character to 41 and 42. Here such of the lighter kerosene as may have been carried over, and gasoline fractions, are condensed, while the so-called incondensable or fixed gases leave the system at 48, and are disposed of in any suitable manner. The various fractions deposited in the series of cooling and condensing chambers may be withdrawn through outlets 49 and led to separate storage containers (not shown). It will be understood that the series of cooling chambers may comprise more than the four units shown, the number used depending upon the extent to which it is desired to carry fractionation. The heavier fractions thus obtained from the vapors from the digesters may be lubricating fractions, and, if desired, a part of such fractions may be conducted to storage tanks 13, 14 for admixture with more crushed shale. The lighter fractions, including kerosene and gasoline, may be marketed, or part, especially kerosene, may be utilized to dilute the residual digestion mixture as hereinafter described.

Means are provided for determining whether or not the digestion has been carried to the desired extent. In the present example, digester 27 is provided with a baffle plate 50 which depends from the dome of the

digester and dips below the level of the liquid therein which, as shown, should be maintained considerably above the upper limits of the screw conveyer 28. The small isolated vapor space 51 thus formed between the baffle plate and the adjacent end of the digester is tapped by a vapor off-take 52 which leads to a small condenser 53. This condenser may be provided with peep holes or observation windows (not shown) whereby the amount of condensate collecting therein may be readily observed and measured. The rapidity with which condensate collects there-in being observed, a measure is thus had of the progress of the digestion. If condensate collects at an abnormally rapid rate this indicates that the oil mixture arriving at the discharge end of the digested system has not been subjected to the heat treatment for the necessary length of time, whereupon this condition can be remedied by slowing down the conveyer mechanism and thus prolonging the time required for the shale and oil mixture to pass through the system.

25 From the last digester 27, the still fluid residual mixture of heavy bitumens and finely divided solid mineral matter is discharged through outlet pipe 54 into a cooling device 55 which may be generally similar in character to the digesters but is not provided with heating means. The mixture is moved at the proper adjustable rate through the cooling apparatus by conveying means such as screw conveyer 56, and gives up a large proportion of its heat to relatively cool oil flowing through coils 57 and 58 and derived from a later stage of the process, as will be herein-after more fully explained.

26 The mixture of residual heavy oils and mineral matters having been thus cooled down sufficiently, most desirably to around 200° F. or thereabouts it may then be diluted with a lighter oil fraction, such as kerosene for example, without occasioning undue volatilization of the mixture. Accordingly the mixture passes from the cooler or heat exchanger 55 into a mixer 58, into the top of which is also introduced through valve pipe 59, kerosene or the like which is supplied from a storage tank 60. In practice it is desirable to dilute with at least an equal volume of kerosene. The provision of baffles 61 or the like in the mixing chamber 58 ensures thorough mingling of the diluent oil with the heavy mixture of residual oil and mineral matter. From the resultant diluted mixture, which may be at a temperature considerably below 200° F., the contained solids may then be separated in any suitable manner; but in view of the very finely divided condition of the solid matter, it is most desirable to make the separation centrifugally; and to this end the diluted mixture is led through pipe 62 into a centrifugal filtering device 63, the separated liquid por-

tion of the mixture passing thence through pipe 64 into a storage tank 65. The relatively cool oil collected in 65 contains both heavy and light fractions, into which it can be separated by any convenient method of fractionation. In the best embodiment of the present process, part or all of the heat required for fractionation is obtained by utilizing said cool oil as the cooling medium in the heat exchanger 55, to reduce the temperature of the heavy residual mixture leaving the digester 27. To this end oil is pumped from 65 through pipe 66 first into the aforementioned pipes 57, arranged outside of and adjacent the bottom and sides of the heat exchanger 55 and thence through the piping 58 which is immersed in the body of oil contained in the cooler. The outside piping 57 is of course arranged in good heat conducting relation to the shell of the heat exchanger, loss of heat to the atmosphere being guarded against by means of insulation lagging 67.

27 From the heat exchanger, the oil which has passed through coils 57 and 58 and thereby has become relatively highly heated by absorption of heat from the residual digestion mixture is now conducted to suitable fractionating apparatus for separating into desired fractions, being additionally heated in any suitable manner en route if necessary, in order to bring it up to the particular topping temperature deemed necessary, say 600° F. or somewhat higher, in a typical instance. In the present example, the hot oil leaving the heat exchanger through pipe 68 is simply sprayed into the upper part of a topping tower 69, the heavier fractions collecting at the bottom of the tower, and being pumped therefrom through pipe 70 to the oil storage 13, 14, for admixture with more crushed shale. The vapors set free in the topping tower 69 and remaining uncondensed, pass out through off-take 71 into one or more condensing chambers 72, in which light fractions may be condensed and collected in any convenient manner.

28 The separated solid matter collected on the revolving filter screen of the centrifugal device may be washed free of adherent heavy oils by washing with gasoline or other light washing solvent supplied through pipe 73 from storage vessel 74. The wash oil thus obtained may be passed into a separate receiving tank 75 with which pipe 64 is connected, the valves shown in the piping system being manipulated to permit this. This wash oil is of suitable character to be used for diluting the digestion mixture and it may accordingly be pumped to tank 60 through pipe 76. The washed solid material remaining on the screen of the centrifugal 63 may be dropped through hopper 77 into a drier 78 to recover therefrom any gasoline or the like which may adhere thereto from the washing. Gasoline or other light vapors

thus obtained may be led off through pipes 79 to a condensing system (not shown), while the dried solid material is discharged at 80, and may or may not be further treated to re-
5 cover additional portions of bituminous mat-
ter remaining therein.

It will be observed that in the process above described, not only does the oil initially mixed with the shale act as a solvent or liquefying 10 agent for the shale bitumens, but both it and said bitumens undergo, during the heat digestion a certain amount of fractionation by straight distillation, and also a mild con-
15 version or transformation of a part of the heavy hydrocarbons into lighter, to an ex-
tent depending largely upon the temperature and duration of digestion, both of which are easily regulable and controllable. No drasti-
20 ctic cracking occurs in the digestion, however,
25 and practically no coke is formed or free car-
bon separated. The digestion vapors being immediately subjected without loss of con-
tained heat units, to cracking treatment, fol-
30 lowed by fractionation largely into light commercial products, a high degree of econ-
omy is made possible by this combined diges-
tion and refining process. The employment
35 of steam in cracking the digestion vapors substantially prevents formation of free car-
bon or coke in that part of the process, thus enabling continuous operation of the com-
plete process over long periods.

Where crude petroleum is employed, wholly or in part, for admixture with the shale to be digested, the benefits of the invention can be realized to the fullest extent; for the novel process permits accomplishing in a combined procedure both distillation and fractionation of petroleum and extraction 40 and separation of shale bitumens in a highly advantageous and efficient manner. Employing crude petroleum as the digestion medium, a somewhat larger proportion should be used in mixture with the shale than where a stripped oil or other heavy fraction or resi-
45 due is used, because it is necessary to allow for the distillation loss during digestion. It may also be advisable, when using crude petroleum, to return to the system a smaller proportion, or even none, of the heavy frac-
50 tions obtained at later stages, since under these circumstances it may be more economi-

cal to refine such heavy fractions entirely by other methods in order to permit handling the maximum amount of crude petroleum in the combined procedure described.

What I claim is:

1. The process of obtaining valuable products from shale like bituminiferous solids which comprises digesting such a shale-like bituminiferous solid in finely divided condition with a heavy mineral oil at temperatures between 500° and 700° F., mixing steam with the evolved vapors and sub-
jecting the mixture to cracking treatment 65 at higher temperatures, fractionally condensing the products of cracking, diluting the residual digestion mixture with a lighter oil, separating solid matter from the diluted mix-
ture, treating the residual oil to obtain a 70 heavy fraction therefrom, and utilizing such heavy fraction and a heavy fraction obtained from the aforesaid cracking products for di-
gestion of a further portion of shale or other bituminiferous solid. 75

2. The process of obtaining valuable hydrocarbon products which comprises digesting a mixture of shale-like bituminiferous solid matter and a mineral oil with the aid of heat, cooling the digestion mixture, sepa-
rating solid matter from the cooled digestion mixture and thereby obtaining liquid bitu-
miniferous material, employing such liquid material in the aforesaid cooling of the diges-
tion mixture, thereby heating said liquid 85 material, and then fractionating said liquid material, at a suitable topping temperature.

3. Apparatus of the character described comprising the combination with a digestion chamber, of a heat exchanger, conduit means 90 arranged to conduct unvaporized material from said digestion chamber to said heat ex-
changer, means for separating solids from liquids, conduit means arranged to conduct cooled material from said heat exchanger to 95 such separating means, means for conducting separated liquid from such separating means to said heat exchanger, fractionating means, and means for conducting said separated liquid from the heat exchanger to said fraction-
ating means. 100

In testimony whereof I hereunto affix my signature.

WM. HUNTLEY HAMPTON.
